UNITED STATES PATENT OFFICE.

GEORGE E. DUNTON, OF NEW YORK, N. Y.

APPARATUS FOR BACKING UP ELECTROTYPE-SHELLS.

1,125,672.

Specification of Letters Patent.

Patented Jan. 19, 1915.

Application filed January 2, 1914. Serial No. 810,022.

To all whom it may concern:

Be it known that I, GEORGE E. DUNTON, residing at New York, in the county of New York and State of New York, a citizen of the United States, have invented a certain new and useful Apparatus for Backing Up Electrotype-Shells; and I do hereby declare the following to be a full, clear, and exact description of the invention, such as will enable others skilled in the art to which it pertains to make and use the same.

My invention relates to improvements in apparatus for backing up electrotype shells for use in forming electrotype plates.

Ever since the conception of the possibility of producing printing plates by the electrotyping process the method of backing up the shells has been the same, namely, the dipping of the melted backing metal, a composition consisting of a combination of lead, tin and antimony, out of the melting pot or kettle with a hand ladle and pouring said melted backing metal over the prepared back of the electrotype shell from this ladle.

To the best of my knowledge and belief no attempt has ever been made to supersede this old and time honored custom which produced very unsatisfactory results and was very severe on the operator doing the work because it meant that the operator must stand close to the side or in front of the heated furnace carrying the melting pot or kettle and dip out the melted metal backing with a hand ladle and pour it over the prepared shell contained in the backing pan placed on a stand directly beside the furnace.

The above operation is mechanically unsatisfactory in that the results obtained are not always uniform or equal, and sometimes when the operator becomes careless, tired or overheated he will throw the melted metal down on the upturned back surface of the shell, which will result in spots directly beneath the splash becoming overheated, compared with the balance of the surface area of the shell, and the unequal contraction resulting from the cooling of the mass results in shrinkages in the backed-up plate which must be pounded out in the subsequent straightening of the surface of the plate detracts from the printing qualities of the finished printing plate.

My invention therefore has for its object to dispense with the old manner of backing up an electrotype shell, which consisted in

dipping the molten metal backing from the melting pot or kettle and pouring it over the back of the electrotype shell in the backing pan by means of a hand ladle, and performing the operation by a new and more convenient manner which consists in transferring the molten metal backing from the melting pot or kettle to the backing pan, and causing it to be distributed over the back of the electrotype shell therein, through a communicating pipe, duct or other means, preferably, by gravity.

It further has for its object to provide means for controlling the flow of the molten metal through the pipe or duct or other means which forms the communication between the melting pot or kettle and the backing pan.

It further has for its object to provide means for transferring the molten metal backing from the melting pot or kettle to the back of the electrotype shell in the backing pan, in such a manner that the molten metal backing will be evenly and uniformly distributed over the entire surface of the back of the shell.

It further has for its object to provide means for melting the solder, or other binder placed on the electrotype shell before applying the molten metal backing, means for transferring the molten metal backing from the melting pot or kettle to the back of the shell in the backing pan and means for cooling the shell and backing.

It still further has for its object to provide means for controlling the flow of molten metal backing from the melting pot or kettle to the backing pan and means for compensating for any excessive amount or overflow of the molten metal backing in said controlling means.

Referring to the drawings: Figure 1 is a side view in elevation. Fig. 2 a top plan view. Figs. 3 and 4 detail top plan and side elevations of the communicating pipe or duct, controlling valve and nozzle. Fig. 5 a detail vertical sectional view, partly in elevation, of the parts shown in Fig. 3. Fig. 6 a bottom plan view of the nozzle. Fig. 7 a horizontal sectional view of the valve taken on the line $x-x$ of Fig. 4. Fig. 8 a similar view to Fig. 7 taken on the line $y-y$ of Fig. 4. Fig. 9 a top plan view of the safety valve or plate.

In the drawings in which similar reference characters denote similar parts

throughout the several views, 1 represents the furnace, used to melt the metal backing for the electrotype shell, 2 the melting pot or kettle in which the metal to form the 5 backing for the shell is placed and melted, 3 the backing pan stand having a pair of side bars 4, on each side, a series of rollers 5 mounted between the side bars, on each side, and 7 being lugs or pins projecting 10 upwardly from the outer ends of the side bars 4 and serving as stops to prevent the backing pans being pushed off the end of the backing stand.

Backing pans 8 and 9 are provided, each 15 having bails or handles 10, the backing pan 8 being shown as resting on leveling screws 11 by which it is adjusted to a perfectly level position. The backing pan 9 is shown as resting on the rollers 5 ready to be moved 20 over the Bunsen burner 12 for the purpose of melting the solder binder to the back of the electrotype shell before applying the molten metal backing. After the molten metal backing is supplied to the backing 25 pans, and they are resting on the leveling screws, it is cooled by means of cool air supplied to the underside of the backing pans by means of a pipe 13, which is connected to a blower 14, or other similar device, and 15 30 is a gate or valve controlling the feed of the cold air. The backing pans are lifted in and out of the melting pot or kettle, preferably, by means of a block and fall 16, having a chain 17 and hook 18, and mounted on 35 a carriage 19 which is provided with wheels 20 designed to travel on a beam 21.

The molten metal backing is transferred 40 from the melting pot or kettle to the backing pans by means of an angular pipe or duct 22 made in two sections 23 and 24 joined or connected by means of an elbow 25. The outer end of the section 24 is provided with a downwardly extending nozzle or spreader 26 for the purpose of modifying 45 or breaking the force of the discharge of the molten metal backing into the backing pans. The inner end of the section 24, mounted in 50 the melting pot or kettle, is connected to a valve 27 which controls the discharge of the molten metal backing from the melting pot or kettle through the angle pipe and nozzle to the backing pans. The valve comprises 55 a casing 28 having a central bore 29, ears or lugs 30 by which it is secured in a hole 31 in the bottom of the melting pot or kettle by screw bolts 32, a boss 33 having a hole 33^a therethrough with which the section 24 connects and communicates, a beveled valve seat 34, a downwardly beveled bottom 35, 60 and a valve plug 36 having radially disposed horizontal inlet ports 37 which communicate with vertical ports 38, extending from end to end of the valve plug, said valve plug having a head 39 with a beveled under surface 65 designed to seat on the valve seat 34.

A vertical hole 40 is provided in the head 39 of the valve plug in which a screw threaded stem 41 is mounted having perforated ears 42 at its upper end, spiral spring 43, a sleeve 44 and a safety valve or plate 45 70 loosely mounted on the stem 41 for the purpose of allowing the escape or return of the excess molten metal backing remaining in the valve to the melting pot or kettle, when the plug is moved downward and contacts with the beveled bottom 35. As the valve plug is moved downward the pressure of the excess metal remaining in the valve plug will cause the safety overflow valve or plate 75 to uncover the vertical ports 38, but just as soon as this pressure is released the spiral spring will cause the said valve to close.

The valve plug is operated by means of a hand lever 46 pivotally mounted on a bracket 47 on the top of the furnace, the 80 inner end of said hand lever being pivoted to the ears on the upper end of the stem 41, and 48 is a locking device, pivoted to the hand lever, which, when in use, contacts or impinges against the base 49 of the bracket 90 47 and thereby locks the valve plug in its closed position.

In using my apparatus I close the controlling valve 27 by moving the valve plug 36 downward, by means of the hand lever 46, 95 until it contacts and is tightly seated on the valve seat 34 of the valve casing, the backing metal is then placed in the melting pot or kettle. I then make a fire in the furnace and after seeing that the inner surfaces of 100 the backing pans are clean and smooth and the leveling screws are adjusted to their proper positions and locked, produce an electrotype shell in the usual manner by the deposition of metal electrolytically upon the 105 surface of a mold made in wax and duly prepared with reference to having its surface made conductive and having deposited a shell, to the desired thickness, upon the surface of the wax mold the shell is carefully removed by pouring boiling water 110 over its surface, with the mold resting in an inclined position in a suitable receptacle, the water being poured from one corner of the mold carefully along the top of the shell, 115 gradually downward, until the heat of the water is transmitted throughout the metal of the shell, which causes the wax of the mold to melt, thus releasing the metal shell, when the shell may be drawn away from the 120 wax mold and the mold removed to a suitable place where the wax is stripped from the pan and remelted for future use. The shell is then thoroughly rinsed in a boiling 125 solution of caustic soda or potash lye to remove the adherent wax, then thoroughly rinsed in hot water to remove all the lye and then plunged into a pickle of dilute sulfuric acid (in water) where it is allowed to remain until ready for backing. I then 130

5 prepare a solution of zinc chlorid, by placing zinc spelter in hydrochloric acid until the hydrogen has been replaced by the zinc by the following reaction,

and as soon as the ebullition has practically subsided take one part of this clear solution of chlorid of zinc and add to it three parts 10 of water to which has been added a few drops of ammonia water to prevent the zinc chlorid deliquesing and depositing in sluggy patches on the back of the shell, when heat is applied for melting the binder 15 of solder foil to the back of the shell. With this solution prepared I thoroughly rinse the shell in running water, to remove all traces of acid pickle, and flow the back, or bright side of the shell, with this ammoniated solution of zinc chlorid which acts 20 as a flux in joining the solder foil binder to the metallic shell, then drain off all the chlorid solution by holding the shell in a perpendicular position over the receptacle 25 containing the solution, lay the shell flat upon its face and cover its exposed back with thin sheets of solder foil. The backing pan having been previously heated by being floated upon the surface of the molten 30 backing metal in the metal pot or kettle of the furnace or by heating the backing pan over a Bunsen or other burner, the shell is carefully laid upon the surface of the backing pan and the solder foil allowed to melt 35 over the back of the shell until it covers the entire surface of the same and enters all the indentures and interstices in the back of the shell, I then remove the backing pan, containing the shell, by lifting the pan by a 40 block and fall, or other suitable means, from the melting pot or kettle and swing the pan over and deposit it upon the tops of the leveling screws on the backing stand directly under the nozzle or spreader of the 45 pipe or duct leading from the melting pot or kettle, then with everything in readiness I carefully raise the hand lever and allow the molten metal backing to flow from the melting pot or kettle, through the valve, 50 angle pipe and nozzle or spreader onto the edge of the backing pan in a small stream and when sufficient molten metal has been supplied to the backing pan to cover the shell the valve is closed by pressing down 55 on the hand lever, then with long thin sticks held in both hands the edges of the metal covered shell are carefully rubbed down until there is no space showing between the edges thereof and the pan, which is termed 60 "sealing the shell to the backing pan," then I again lift the valve by raising the hand lever, opening the pipe or duct to its full capacity, and allow the molten metal to again flow from the melting pot or kettle, 65 through the valve, angle pipe or duct and

out of the nozzle or spreader into the backing pan until the molten metal has attained the required level in the backing pan and covered the shell to the desired depth, by which the thickness of the plate is determined, the valve is again closed by pressing down upon the hand lever until the valve plug is seated upon its seat and the supply of molten backing metal is shut off. The gate in the air pipe is then opened and a 70 blast of cool air is allowed to act on the bottom of the backing pan until such time as the metal backing becomes set or sufficiently rigid or hard to allow the backing pan to be lifted and placed upon the rollers when 75 it is pushed away from the furnace and allowed to stand until it is sufficiently cooled to allow the removal of the plate from the pan. The plate is then removed to the cleaner's bench where it is washed in kerosene oil, or some other detergent, and in heated lye, rinsed in water and dried in sawdust when it is taken to the circular saw table where it is cut up and goes through the customary operations of finishing common 80 to the electrotyping art. In the meantime the backing pan has been washed in a weak solution of lye, dried and carefully brushed off when it is ready to have the entire operation repeated. 85

90 The backing pan is preferably situated in a lower horizontal plane than the melting pot or kettle for the purpose of allowing the molten metal backing to flow from the melting pot or kettle into the backing pan by 95 gravity.

I do not wish to be understood as limiting myself to the exact details of construction and arrangement as herein described and illustrated, as it is manifest that variations and modifications may be made in the features of construction and arrangement in the adaptation of the device to the various conditions of use without departing from the spirit and scope of my invention and 100 improvements. I therefore reserve the right to all such variations and modifications as properly fall within the scope of my invention and the terms of the following claims. 105

110 What I claim is:—

1. In an apparatus for backing up electrotype shells, a melting pot for melting the backing metal, a backing pan, a pipe or duct communicating with said melting pot and backing pan, a valve connected with said pipe or duct and melting pot provided with a casing having a plug with ports, spring controlled means for normally closing said ports and means for operating said plug whereby the molten metal in said ports is 115 caused to open the same, substantially as described. 120

2. In an apparatus for backing up electrotype shells, a melting pot for melting the backing metal, a backing pan, a pipe or duct 130

forming a communication between said melting pot and backing pan, a valve connected with said pipe or duct and melting pot provided with a casing having a plug with 5 horizontal and vertical ports, a valve or plate resiliently mounted on the top of said plug which normally closes said vertical ports but which is adapted to be moved upward and uncover said ports, when the 10 plug is moved downward, by the pressure of the excess metal in said vertical ports of said plug, substantially as described.

3. In an apparatus for backing up electrotype shells, a melting pot for melting the 15 backing metal, a backing pan, a pipe or duct forming a communication between said melting pot and backing pan, a nozzle on the outer end of said pipe or duct having an elongated unrestricted discharge opening for 20 delivering molten metal to the backing pan, substantially as described.

4. In an apparatus for backing up electrotype shells, a melting pot for melting the 25 backing metal, a backing pan, a pipe or duct forming a communication between said melting pot and backing pan and furnishing a communication between them, means connected to the end of said pipe or duct for spreading the molten metal backing into a 30 broad sheet as it is discharged from said pipe or duct in its delivery to the backing pan, substantially as described.

5. In an apparatus for backing up electrotype shells, a melting pot for melting the 35 backing metal, a backing pan, a pipe or duct forming a communication between said melting pot and backing pan, a valve having a casing connected with said pipe or duct and melting pot provided with a plug having 40 horizontal ports opened and closed by the vertical movement of said plug, vertical ports with which said horizontal ports communicate, means for automatically controlling the opening of said vertical ports and 45 means for operating said plug, whereby the molten metal in said vertical ports is caused to open the same, substantially as described.

6. In an apparatus for backing up electrotype shells, a melting pot for melting the 50 backing metal, a backing pan, a pipe or duct forming a communication between said melting pot and backing pan, a valve having a casing connected with said pipe or duct and the melting pot, a plug provided with a series of horizontal ports opened and closed 55 by the vertical movement of said plug, a series of vertical ports communicating with the horizontal ports and resiliently mounted means on the top of said plug for opening and closing said vertical ports, substantially 60 as described.

7. In an apparatus for backing up electrotype shells, a melting pot for melting the 65 backing metal, a backing pan, a pipe or duct forming a communication between the melting pot and backing pan, a valve mounted in the melting pot provided with a casing connected to said pipe or duct, a plug within 70 said casing having communicating horizontal and vertical ports, by which the molten metal backing enters said plug, means for controlling the inlet of said molten metal backing and means for allowing the excess molten metal to be forced out of said plug, 75 substantially as described.

8. In an apparatus for backing up electrotype shells, a melting pot for melting the 80 backing metal, a backing pan, a pipe or duct for forming a communication between the melting pot and the backing pan, a nozzle 85 connected to said pipe or duct, a valve mounted in the melting pot provided with a casing connected to said pipe or duct, a plug within said casing having horizontal ports and vertical ports extending from end to end of 85 said plug and communicating with said horizontal ports, substantially as described.

In testimony whereof I affix my signature in the presence of two witnesses.

GEORGE E. DUNTON.
